UNITED STATES PATENT OFFICE.

HUGH McCABE, OF LAWRENCE, MASSACHUSETTS.

FEED-WATER REGULATOR.

1,148,107.

Specification of Letters Patent.

Patented July 27, 1915.

Application filed April 16, 1908. Serial No. 427,839.

To all whom it may concern:

Be it known that I, HUGH McCABE, a citizen of the United States, residing at Lawrence, in the county of Essex and State of Massachusetts, have invented certain new and useful Improvements in Feed-Water Regulators; and I do hereby declare the following to be a full, clear, and exact description of the invention, such as will enable others skilled in the art to which it appertains to make and use the same.

This invention relates to feed-water regulators.

Its object is to re-organize, simplify and improve feed-water regulators for steam boilers; the invention consists in the regulator hereinafter described and particularly defined in the claims.

Following is a description of the invention, reference being made to the accompanying drawings, in which,

Figure 1 is a front elevation of the preferred embodiment of the invention; Fig. 2 is a side elevation of the same, the portion in front of the line 2—2 Fig. 1 being removed for the sake of clearness; Fig. 3 is a vertical sectional view of the controlling valve on line 3—3, Fig. 2 with the side elevation of balance lever; Fig. 4 is a view partly in longitudinal vertical section and partly in elevation of the lever support; and Fig. 5 is a vertical sectional view of the supply valve.

The general operation of the invention is as follows:—When the water in the boiler falls below a certain level, it permits the steam to flow through a pipe which is opened by the drop of the water in the water column below the end of the pipe, and the steam flows through a trunnion into a balanced lever having at one end a weight and at the other end a large hollow ball. Normally, the ball is filled with water which overbalances the weight upon the other end of the lever. When the steam flows into the ball and displaces the water therein, the weight on the other end of the balance lever over-balances the ball and the weight drops and thereupon opens a controlling valve and allows steam to flow through to a supply valve of a water supplying means for supplying water to the boiler. The opening of the supply valve permits steam from the

boiler to flow through to a steam pump which pumps the water to the boiler, or permits water to flow from a hydrostatic pressure reservoir to the boiler. When the level of the water in the boiler has been raised above the end of this pipe, thereby preventing access of steam to the boiler, the water flows into the ball thereby causing it to overbalance the weight and to drop. This closes the controlling valve, shutting off the supply of steam to the supply valve and at the same time opens an exhaust valve allowing the pressure on the supply valve to be reduced and the supply valve thereupon automatically closes shutting off the supply of steam or water.

In the illustrated embodiment of the invention, a water column 1 is connected to the boiler by a pipe 2 extending from the top of the water column to the steam space in the boiler, and by a pipe 3 from the lower end of the water column to the boiler below the water level. The lower end of the water column normally extends below the lowest level of the water in the boiler.

A controlling valve is connected to the upper or steam portion of the water column, by a pipe 4 extending upwardly to a valve 80 casing 5 which is laterally supported by a brace 6 secured to the pipe 2. Within the casing 5 is a valve chamber 7 having an outlet 8 connected to a supply valve and the supply of steam from the pipe 4 to the supply valve is controlled by a controlling valve 9 mounted on the lower end of a stem 10 which passes through an exhaust chamber 11 having an outlet or exhaust 12. The stem 10 is slotted just above the controlling valve 9 to permit the steam to escape from the valve chamber into the exhaust chamber when the controlling valve 9 is closed. Upon the upper end of the stem 10 is mounted a button 13 which moves within a cup 14 and the controlling valve 9 is maintained in an open position by a helical spring 15 abutting against the button 13 and the bottom of the cup 14. When the button is pressed downwardly the controlling valve 100 9 is thereby closed and when the pressure is released the spring 15 pushes the button 13 upwardly and opens the controlling valve 9.

The operation of the controlling valve is

regulated by a balanced lever. From the valve casing 5 extends upwardly a yoke 16, the ends 17 and 18 of which are hollow and form bearings for two hollow trunnions 19 and 20 respectively. A pipe 21 extends from the water column at the critical line to the hollow end 17 of the yoke and a similar pipe 22 runs from the lower portion of the water column to the other end 18 of the yoke. The pipes 4, 21 and 22 are all controlled by ordinary valves 23 which are normally open and should never be closed except when it may be necessary to make repairs. The ends of the trunnions lying within the hollow ends of the yoke are held steam-tight by means of packing 24 compressed by ported glands 25 operated by hand wheels 26 on stems 27 which screw into the ends of the yoke ends 17 and 18 and are held by check nuts 28. The other ends of the trunnions extend toward the center of the yoke and are threaded in order to engage threaded bores and thereby pivotally support between them a balanced casting 29 having chambers 30 and 31 which are continuations respectively of the hollow trunnions 19 and 20. These chambers 30 and 31 open respectively into two pipes 32 and 33 which extend horizontally from the casting 29 and enter a ball 34 supported by them, the pipe 32 extending within the ball nearly to the top. On the opposite side of the casting 29 is a horizontally extending rod 35 carrying a weight 36 and the casting 29 with the rod and weight on one side and the pipes and ball on the other side form a balanced lever pivotally mounted on the trunnions. When the ball is full of water it over-balances the weight and retains the lever in a horizontal position and in that position, the under side of the casting 29 presses downwardly upon the button 13 and keeps the controlling valve 9 closed but, when the ball is empty the weight over-balances and causes the lever to revolve on the trunnions and the casting 29 to move upwardly thereby permitting the controlling valve to be opened by the spring 15. A screwstop 37 limits the downward movement of the weighted end of the lever. From the outlet 8 in the valve chamber 7, a pipe 38 extends to a chamber 39 in a casing 40 for the purpose of carrying steam to open a supply valve. Within the chamber 39 is a piston 41 mounted on a stem 42, the lower end of which carries a supply valve 43 for opening and closing the opening between an inlet chamber 44 connected to a steam supply and an outlet chamber 45 connected to a steam pump. In the chamber 39 the stem 42 is held steam-tight by packing 46 compressed by a gland 47. Around the upper portion of the valve stem is a helical spring 48, the lower end abutting against the top of the piston 41 and the upper end abutting

against a spring cap 49 of the casing 40, which exerts pressure upon the piston and tends to keep the supply valve 43 closed at all times. For convenience in operating the supply valve independently of steam pressure, the upper end of the stem 42 is screw-threaded and provided with a hand wheel 50, the hub 51 of which seats on the top of the spring cap 49, and the supply valve is raised or lowered by turning the hand wheel. 70 This device operates in detail as follows:— When the water in the boiler falls below the critical line, it opens the end of the pipe 21 in the water column and permits steam to flow up through the pipe 21, through the 80 hollow end 17 of the yoke 16, the trunnion 19, the chamber 30 of the balanced casting 29 and the pipe 32 into the ball 34 thereby displacing the water which flows out of the ball through the pipe 33, the chamber 31 85 in the balanced casting 29, through the trunnion 20 and the end 18 of the yoke 16 into the pipe 22 and back into the water column. With this displacement of the water in the ball by steam, the weight 36 over-balances 90 the ball and causes the balanced lever to tip and the casting 29 moves upwardly and permits the spring 15 to open the controlling valve 9 and admit steam from the upper portion of the water column through the 95 pipe 4, the valve chamber 7 and pipe 38 to the chamber 39 where the steam pressure moves the piston 41 upwardly and lifts the supply valve 43. This allows steam to flow to the steam pump, by which the boiler is 100 fed. When the water in the boiler rises above the mouth of the pipe 21 then the supply of steam through that pipe to the balanced lever and ball is shut off and the condensation of steam in those portions causes 105 the water to flow up through pipes 21 and 22, the trunnions 19 and 20, chambers 30 and 31, and pipes 32 and 33 into the ball 34, and the ball gradually fills. In this state, it over-balances the weight 36 and causes 110 the balanced lever to swing again to a horizontal position and the lower side of the casting 29 closes the controlling valve 9, shutting off the supply of steam from the pipe 4 to the supply valve. At the same time, the steam in the chamber 39 and pipe 38 exhausts through the slots on the stem 10 to the exhaust chamber 11. This reduces the pressure in the chamber 39 and the spring 49 forces down the piston 41 and supply valve 43 thereby shutting off the supply of steam to the steam pump or the supply of water from the hydrostatic pressure reservoir to the boiler as the case may be. 115

An important feature of the invention resides in the arrangement of the controlling valve which controls the flow of steam to the supply valve. The valve, it will be noted, closes against the pressure of the steam, as a consequence of which, when the lever tips 120

and the pressure which the latter exerts on this valve is relieved, the valve under the influence of the boiler pressure assisted by its spring is moved away from its seat with great certainty of operation. At the same time this same valve also operates to close the exhaust from the supply valve and the steam pressure is availed of to hold the exhaust opening closed. The making of the 10 exhaust and the steam valve in one piece inures to the simplicity of the apparatus by the reduction not only in the number of moving parts but by the elimination of friction incident thereto. Furthermore, it will 15 be observed that the controlling valve closing as it does against the pressure of the steam needs no stuffing gland. This contributes to the certainty of the operation of the apparatus by the elimination of friction 20 incident to the use of such glands.

In the present construction, it is to be observed, the pressures on the opposite trunnions are equal, as a result of which there is no end thrust on the balanced lever casting. This is a feature of practical importance as it reduces the friction required to be overcome in the tipping of the lever and thereby contributes to the certainty of operation of the apparatus. It is also to be observed that the parts are simple and so arranged that the device requires little care and is therefore well adapted for use in boiler rooms and the like where such mechanisms are subjected to a minimum of care 35 and a maximum of dirt and abuse.

The present invention is not limited to the specific construction illustrated herein as it may be embodied in other forms.

What is claimed is:-

40 1. A water feed regulator for boilers, having, in combination, water supplying means, a controlling valve for controlling the starting and stopping of the water supplying means, a balanced lever for actuating the 45 controlling valve supported on hollow trunnions, supports for the trunnions having passages communicating with the passages of the hollow trunnions, and means within the passages in the supports comprising 50 ported glands for packing the trunnions, substantially as described.

2. A water-feed regulator for boilers having, in combination, a steam actuated water supplying means, a pipe connection between 55 said means and the boiler and a controlling valve in the said connection, and mechanism for operating the valve including a frame of a substantially Y shape having a controlling valve inclosed in the lower part 60 of the Y and having a steam connection through one branch of the Y and a water connection through the other branch of the Y, a hollow ball, a ball-supporting lever having trunnions supported in the branches of 65 the Y-shaped frame and having a steam pas-

sage through one trunnion to the steam connection in one branch of the Y and having a water passage through the other trunnion to the water connection in the other branch of the Y, said lever being situated immediately above 70 the valve, and an operating connection between the lever and valve, substantially as described.

3. A water-feed regulator for boilers having, in combination, a steam actuated supply valve for regulating the supply of water to the boiler, a valve casing having a steam inlet from the boiler, a steam outlet connected to the supply valve and an exhaust passage, a controlling valve within the casing having oppositely disposed seats for controlling the inlet and exhaust passages respectively and closing the inlet passage against the boiler pressure, a balanced lever, a hollow ball carried by the lever, counter-balancing means acting on the lever to counterbalance the hollow ball, steam and water connections between the hollow ball and the boiler, said balanced lever being arranged to engage and close the inlet passage of the 90 controlling valve when tilted in one direction, and a spring assisting the boiler pressure for opening the inlet passage of the controlling valve when the lever is tilted in the other direction, substantially as de- 95 scribed.

4. A water-feed regulator for boilers having, in combination, a steam actuated water supplying means, a pipe connection between said means and the boiler, a controlling 100 valve in the pipe connection opening against the boiler pressure and having a valve stem projecting outside of the valve casing, a balanced lever having provision so as to be tilted in either direction depending upon the 105 water line of the boiler, said lever loosely engaging the projecting end of the valve stem to close the valve when tilted in one direction, and a spring assisting the boiler pressure for opening the valve when the 110 lever is tilted in the other direction, substantially as described.

5. A water-feed regulator for boilers having, in combination, a steam actuated water supplying means, a pipe connection between 115 said means and the boiler and a controlling valve in the said pipe connection, and mechanism for operating the valve including a frame of a substantially Y shape having a controlling valve inclosed in the lower part 120 of the Y and having a steam connection through one branch of the Y and a water connection through the other branch of the Y, a hollow ball, a ball-supporting lever having trunnions supported in the branches of 125 the Y-shaped frame and having a steam passage through one trunnion to the steam connection in one branch of the Y and having a water passage through the other trunnion to the water connection in the other branch 130

of the Y, said lever being situated immediately above the valve, and an operating connection between the lever and valve including a valve stem extending from the valve in the crotch between the branches of the Y and arranged to be moved by the lever, substantially as described.

In testimony whereof I affix my signature, in presence of two witnesses.

HUGH McCABE.
